UNITED STATES PATENT OFFICE.

DIMITRI SENSAUD LAVAUD, OTHERWISE KNOWN AS DIMITRI SENSAUD DE LAVAUD, OF TORONTO, ONTARIO, CANADA, BERNARD FRANCIS CLARK, OF LONDON, AND CHARLES WILLIAM BAINES, OF MELTON MOBRAY, ENGLAND, ASSIGNORS TO THE METALLURGICAL PLANT CONSTRUCTION COMPANY LIMITED, OF MANCHESTER, ENGLAND, A COMPANY OF GREAT BRITAIN.

APPARATUS FOR USE IN TEMPERING AND ANNEALING.

1,420,379.

Specification of Letters Patent. Patented June 20, 1922.

Application filed March 2, 1922. Serial No. 540,480.

To all whom it may concern:

Be it known that we, DIMITRI SENSAUD LAVAUD, otherwise known as DIMITRI SENSAUD DE LAVAUD, a Brazilian citizen, and resident of Toronto, in the Dominion of Canada, BERNARD FRANCIS CLARK, a subject of the King of Great Britain, and resident of London, England, and CHARLES WILLIAM BAINES, a subject of the King of Great Britain, and resident of Melton Mowbray, England, have invented new and useful Improvements in or Relating to Apparatus for Use in Tempering and Annealing, of which the following is a specification.

15 This invention has reference to apparatus for use in tempering and annealing. The primary object of the invention is to provide improvements in plants wherein the heat contained in metallic or other objects 20 after heat treatment, such as annealing, and given off in a cooling chamber to which the objects when sufficiently heated are transferred is usefully employed.

In accordance with this invention heat 25 utilization apparatus such as a steam generator with or without a superheater is placed in the cooling chamber to usefully absorb the heat given off by the cooling objects as distinct from absorbing the heat 30 by water jacketing the wall of the chamber. Moreover when objects are not passing through the heating chamber or furnace and cooling chamber the heat of the hot air or 35 gases normally used in the heating chamber is utilized by passing the said air or gases into and through the cooling chamber for absorption of their heat by the heat utilizing apparatus therein.

A further feature of the invention consists 40 in the provision of means whereby each treated object after passage through the cooling chamber may be subjected to a quenching operation or to an operation which coats or covers it with a preservative 45 or other composition.

To enable the invention to be clearly understood and readily carried into effect the same will now be described more fully with reference to the accompanying drawings in 50 which:—

Figure 1 is a longitudinal sectional elevation of a complete heating and cooling

plant embodying the features of our invention and adapted particularly for the heat treatment of metal pipes.

Figure 2 is a sectional plan approximately on the lines 2—2, 2^a—2^a of Figure 1.

Figures 3, 4 and 5 are vertical cross-sectional views taken on the lines 3—3, 4—4 and 5—5 respectively on Figure 2.

The heating chamber is designated by the reference letter A, the cooling chamber by B, and the transporting means by C. Beneath the heating chamber A are regenerators *a* and within and in the upper region 65 of the cooling chamber B is a tubular steam generator *b*. The transporting means C are in the form of a pair of endless conveyor chains having spacing prongs *c*. The pipes gravitate down rails D from the feeding 70 end outside the chamber A to the delivery end outside the chamber B under the control of the chains C which pass around the wheels E driven by a motor F. The chains themselves are supported and guided during their travel by upper and lower guide rails G and H. J is a receptacle containing water, oil or other liquid to which the pipes pass and through which they are conveyed by the star shaped revolving conveyor K 80 driven from the motor F. The gearing from the motor F to the chain C on the one hand and to the revolving conveyor K on the other hand is such that the spokes of the conveyor K co-operate in succession with 85 the successive pipes escaping from the chain C.

L is a tunnel communicating outwardly with a smoke stack and inwardly with a central passage M situated beneath the cooling chamber and controlled by dampers N and O adapted to be raised and lowered alternately by gearing operated from a common gear wheel P actuated by gearing outside the plant. When the damper N is 90 down and the damper O is up, there is a clear way from the chamber B down the vertical shafts Q and along passage M to the tunnel L. On the other hand when as under normal working conditions the damper N is 95 up and the damper O is down, there is a clear way for the hot air or gases from the chamber A down the vertical passages A³ and through the regenerators *a* to the pas-

sage M and thence to the tunnel L. The portion of the central passage M nearest the regenerators a is divided by a partition m and the two branch passages are controlled by two dampers R and S operated mechanically from outside the plant by chains and gear wheels r and s shown conventionally in Fig. 2. By means of these dampers R and S either of the corresponding passages may be closed and the corresponding regenerators a rendered inoperative.

The heating chamber A has side openings controlled by balanced doors A' and communicates direct with the cooling chamber by the archway A². A³ and A⁴ are vertical passages communicating with the heating chamber and the regenerators a. The passage A⁴ is the uptake passage from the regenerators to the combustion chamber.

20 The air and gas for combustion for heating the chamber A is led through suitable passages into the mixing chamber A⁵.

From the foregoing description and from a consideration of the drawings it will be understood that during the normal operation of the furnace the damper N is up and the damper O is down and the heated articles pass into the chamber A where they are heated by contact with the hot air or gases and then pass into the cooling chamber B where they give off their heat to the steam generator and then pass through the quenching or coating bath or receptacle J. When articles are not being treated but it is nevertheless desired to keep the heating chamber A hot in readiness, the damper N is lowered and the damper O is raised so that the hot air or gases proceeding from the chamber A pass through the archway A² directly to and 40 through the cooling chamber B where the heat is usefully absorbed by the contents of the steam generator the said air or gases proceeding from the chamber B down the shafts Q and along passage M to the tunnel L.

45 What we claim and desire to secure by Letters Patent of the United States is:—

1. Apparatus for use in heat treatments such as tempering and annealing, comprising a heating chamber, a cooling chamber, and heat utilizing apparatus comprising a steam generator placed in the cooling chamber to absorb the heat given off by the heated objects when in the cooling chamber.

2. In an annealing furnace having a heating chamber, a cooling chamber containing means for absorbing heat from the objects or articles as they cool, and means for feeding the objects or articles through said chambers, the method which comprises normally leading the gases of combustion away from the cooling chamber when said chambers are in use and diverting said gases through said cooling chamber when said chambers are not in use. 55

3. In an annealing furnace having a heating chamber, a cooling chamber containing means for absorbing heat from the objects or articles as they cool, means for feeding the objects or articles through said chambers, and a regenerator, the method which comprises normally leading the gases of combustion through said regenerator when said chambers are in use and diverting said gases away from said regenerator and 70 through said cooling chamber when said chambers are not in use. 75

4. Apparatus for use in heat treatments such as tempering and annealing, comprising a heating chamber, a cooling chamber in connection with said heating chamber, heat utilizing means in said cooling chamber, a conveyor for transporting the metallic or other objects through said heating chamber and cooling chamber, and means whereby, 80 when objects are not passing through the heating chamber and cooling chamber but said heating chamber is being maintained hot the hot air or gases therefrom are directed into the cooling chamber for absorption 85 of their heat by the heat utilizing means therein. 90

5. Apparatus comprising a heating chamber, a cooling chamber communicating with said heating chamber, a steam generator in 95 said cooling chamber, transporting means for travel through said chambers, means controlling the passage of heating medium to and from said chambers and between them and means for subjecting the heat treated articles to a liquid quenching or coating operation. 100

DIMITRI SENSAUD LAVAUD.

BERNARD FRANCIS CLARK.

CHARLES WILLIAM BAINES.
